AUTOMATIC INTERLOCK FOR PUSHER MACHINES AND COKE GUIDE MACHINES

Paul Howard Lavely, Pittsburgh, Pa., assignor to Koppers Company, Inc., a corporation of Delaware

Application January 14, 1947, Serial No. 721,910
In Great Britain January 16, 1946

7 Claims. (Cl. 214—23)

1

This invention relates in general to improvements in interlocking apparatus between the pusher machine and the coke guide machine on opposite sides of horizontal coke oven batteries, for making certain that the operator of the pusher machine, on one side of the battery, can actuate the pusher ram for pushing coke from only those oven chambers from which the operator on the coke discharge side, on the opposite side of the battery, has the coke oven door removed and out of the way, and the coke guide in place on the door frame, for passing the incandescent coke over the coke side bench to a coke quenching car, or wharf or other means for receiving the finished incandescent coke cake for quenching.

More particularly the present invention is directed to improvements in the automaticity of operation of pneumatically actuated interlocking mechanism for the aforesaid purpose, and of the type comprising fluid-pressure lines individualized to the respective oven chambers, and leading from adjacent the doorways on the coke side of the battery to the pusher side of the battery where they may individually actuate operating means for a limit switch controlling an electrical circuit, also under the control of the operator of the pusher machine, for advancing a reciprocating pusher ram into an oven chamber, from which he has previously removed the pusher side coke oven door, to push the finished coke from the chamber, out through the coke side doorway, through the coke guide, onto a quenching car or coke wharf or other apparatus for receiving the finished incandescent coke cake.

In such form of apparatus the pneumatic actuation of individual fluid pressure lines, for operating the limit switch in the pusher ram operating circuit, is controlled individually by the co-action with a portion of the lines at the coke side doorways of a means operable from the coke guide machine, in its position when the coke guide is in place on the opened oven chamber doorway, for causing, on the one hand, pneumatic pressure in the lines to actuate, and on the other hand release, the operating means on the pusher machine on the opposite side of the battery, for operating the limit switch, in the electrical circuit for advancing the pusher ram into the selected oven chamber, and for stopping it from advancing.

An important feature of the present invention is the provision of means for automatically interrupting the circuit for the motor for driving the coke guide machine from chamber to chamber

2

along the battery, when the aforesaid means operable from said machine for co-action with the individual fluid pressure lines is so co-acting for operation of the pusher ram on the opposite side of the battery.

A further important feature of the present invention is the like provision of means for automatically interrupting the circuit for the motor for driving the pusher machine from chamber to chamber along side the pusher side of the battery, when the apparatus is interlocked pneumatically from the coke guide side in a manner to actuate the limit switch for the pusher ram, permitting its circuit to advance the pusher ram.

15 A further important feature of the present invention is the provision of improved means employing the movement of the pusher machine into position at the ends of the respective oven chamber, for automatically connecting the pusher machine portion of the interlocking mechanism individually with the individual fluid pressure lines, when the latter are pneumatically set for actuation of the pusher ram for the respective oven chambers.

20 25 The present invention, further, combines with the last mentioned feature, the novel provision for manual interconnection of the pusher ram control mechanism with the individual fluid pressure lines for optional, but alternative, operation as may be required under the exigencies of coke plant operation to alleviate conditions which otherwise might interfere with the necessary timely carrying out of the coke oven battery pushing schedule, which often is a matter of 30 minutes, and unless timely attended to might otherwise be of serious consequences in over-coking of coke and over-heating of the oven masonry.

35 40 The invention has for further objects such other improvements and such other operative advantages or results as may be found to obtain in the apparatus hereinafter described and claimed.

In the accompanying drawing forming part of 45 this specification, and showing, for purposes of exemplification, preferred form of apparatus in which the invention is embodied and practised, without however, limiting the claimed invention specifically to such illustrated instance:

50 55 Figure 1 is a transverse section partly in elevation illustrating a conventional form of coke oven, pusher machine, and coke guide machine equipped with automatic control apparatus embodying the present invention;

Figure 1a is an enlarged end elevational view

of a portion of Fig. 1, illustrating the mechanism, for employing the movement of the pusher machine for automatically connecting the pusher machine portion of the interlocking mechanism individually with the individual fluid pressure lines;

Figure 2 is a top plan view of the apparatus shown in Figure 1;

Figure 3 is a diagrammatic side elevational view taken on the line 3—3 of Figure 1, to illustrate the relationship of the coke guide machine relative to the individual fluid pressure lines.

Referring to the drawings, 10 represents a conventional form of coke oven battery of horizontal by-product coke ovens of the underjet, cross-regenerative type.

The battery comprises a series of alternate coking chambers 11 and intermediate heating walls 12, which extend transversely of the battery 10 from the coke side 13 to the pusher side 14. These are supported by spaced transverse pillar walls 15 forming between them regenerator spaces or chambers 16, which are communicably connected by regenerator ducts 17 and discharge ports (not shown) with combustion flues (not shown) formed within the heating walls 12. The whole super-structure is of masonry which is supported on a concrete oven-mat or pad 18 which is supported above accessible basement passageways 19 by means of transverse beams 20, and longitudinal beams 21 at the opposite sides of the battery, the beams 20 being in turn supported on columns 22 resting on a foundation mat or pad (not shown).

The coking chambers 11 are closed on the coke discharge side by means of removable replaceable doors 23, and on the pusher side by means of similar doors 24. The doors 24 are, as usual, provided with a leveller door in their tops for the insertion and reciprocation of the usual leveller-bar (not shown) from the pusher machine 25, for levelling the coal, when newly charged into the oven chambers through charging holes therefor in the oven roof 26.

The gas distilled off during carbonization in the respective oven chambers 11 flows off through their gas collecting crown spaces 27 to an offtake 28 at one end in the oven roof 26, which offtakes 28 are each provided, as usually, with an ascension pipe connecting with a gas collecting main (not shown).

For heating the oven the regenerators are, usually, connected in pairs with the hetaing flues, for alternate operation, for inflow of air and gas separately and simultaneously, and for concurrent outflow of waste gas, in the two regenerative reversal periods or phases. These regenerators are also connected up, as usually, with a lean gas and an air supply (not shown) for the purpose, and the regenerators are also provided with air connections for the regenerators for lean gas pre-heating, for optional alternative rich-fuel gas underfiring of the ovens. For this latter purpose, each combustion flue is, conventionally provided with vertical underjet riser-ducts (not shown) leading from the basement passageways upwardly through the pillar walls separating the regenerators to the individual combustion flues in the heating walls.

The masonry of the battery is tied together by means of buckstays 29 at the coke and pusher sides of the battery. These buckstays are disposed vertically alongside the ends of the heating walls 12, and are supported at their lower ends by the beams 21, in spaced relation so as to leave

the doorways of the oven chambers accessible for pushing of coke from the coking chambers. For this purpose there is provided a coke-bench 30 and a pusher bench or platform 31.

5 For pushing the finished coke from the ovens individually, there is provided, on the pusher side of the battery, a pusher machine indicated generally at 25 which travels alongside the battery, from oven chamber to oven chamber, by means of a carriage 32 having wheels 33 riding on rails 34 at ground level.

This pusher machine carries, as conventional, the reciprocable leveler bar, with electric motor drive and circuit therefor (not shown), a coke oven door extracting and replacing machine, with electric motor operated mechanism and electric circuit therefor (not shown), a motor drive, with circuit therefor (also all not shown) for propelling the entire pusher machine alongside the 15 battery on the rails, in addition to the pusher ram 35, and electric motor drive mechanism 36 therefor, including an electric circuit for reciprocating the pusher ram 35 forwardly into, through, and reversely, backwardly out of the respective oven 20 chambers.

On the coke discharge side of the oven battery, in normal operation, the doors on that end of the oven chambers are removed and the finished incandescent coke cake discharged individually 30 in accordance with a predetermined sequence, termed the pushing schedule in this art.

For this purpose, as conventional a coke guide machine 37 is provided having a truck 38 with wheels 39 which ride on rails 40 on the coke 35 bench 30. This coke guide machine 37 also carries a door extractor machine 41 for extracting and replacing the coke-side oven-doors individually. This door extractor machine is indicated diagrammatically at 41. It is also provided with an 40 electric motor driven operated mechanism and electric circuits for the various manipulations of this extractor machine. The coke guide machine 37 also carries a motor and electric circuit therefor (not shown) for propelling the entire coke 45 guide machine along the coke bench from oven door 23 to oven door 23. In addition it has an operating platform and a coke guide 42, which guide is reciprocable into and out of engagement with the end of the opened doorway of an oven 50 chamber, for discharge passage of hot (incandescent) coke from the oven over the coke bench to an awaiting quenching car or coke wharf or other means (not shown) for further processing of the incandescent coke after it issues from the 55 coking chamber. The coke guide machine is provided with a drive, usually a rack and pinion, for mechanically pressing the coke guide into and out of engagement with the ends of the coke oven chamber doorway between the buckstays.

60 For convenience of operation, the coke guide is mounted, as shown, on a separate truck, connected at 43 as a trailer to the rest of the coke guide machine, the door extractor machine 41 is disposed near the opposite end of the coke guide machine 37 and the remaining equipment and operating platform disposed between the two.

In this type of coke oven, it is customary to 70 push and charge the ovens in a regular sequence but so that adjacent oven chambers are not pushed consecutively, and so great care must be exercised by the operators of the two machines, who can not see or talk with each other because of the intervening coke oven battery, to adhere strictly to the pushing schedule.

75 The operator of the coke guide machine first

removes the coke oven doors 23 of the coke oven designated in the pushing schedule and then moves the coke guide machine along the battery to bring the coke guide 42 into alignment with the open oven doorway, and then is operated the mechanism to press the coke guide against the open doorway structure. On the opposite side of the battery the operator of the pusher machine 25 brings it into position to remove the door 24 at that end of this same oven chamber and after its removal aligns the pusher ram with the open doorway preparatory to advancing the ram 35 into the opened chamber. Upon a given signal the pusher machine operator manipulates the controller for the motor 36 to advance the ram 35 and push the hot coke cake horizontally through and out of the chamber, through the coke guide 42 to the quenching car or wharf (not shown) on the opposite side of the battery. The pusher ram extends all the way through the oven chamber to the opposite doorway. It is then retracted fully from the oven chamber and over the pusher machine. The two doors are then replaced. A new coal charge is filled in through the oven roof, and this charge levelled by reciprocation of the leveller bar from the pusher machine through the leveller door in the pusher side coke oven door while it is sealed gas tight on the end of the oven chamber.

After this is done the operators operate the motors to propel their respective machines along the battery sides to the next oven designated on the pushing schedule, and repeat there the same operations.

Because of the blindness of this coordination, and the staggering of the ovens being pushed, there is always the chance that the operator of the pusher machine may remove a door 24 from an oven which does not correspond with the oven from which the door 23 has been removed by the operator of the coke guide machine, since each operator may, at times through error remove a different door from that called for by the schedule. And, on signal, the operator of the pusher machine, not knowing of the error, may cause the ram 35 to enter and push an oven chamber from which the door 23 has not been removed, or the coke guide 42 properly set in place, at the opposite end of the coke oven that the pusher machine operator is pushing. Serious damage may result because of the pressure exerted on the oven structure and on the coke side door by the action of the powerful ram.

To prevent this there is conventionally provided fluid pressure operated means, pneumatically operated, and individualized to the respective oven chambers, to prevent the pusher ram from being advanced into an oven chamber until the coke oven door on the opposite end of that chamber has been removed, and the coke guide is in place, and all under the control of an operator on the coke guide machine.

This has taken the form of separate fluid pressure lines 44, each individual to one of the oven chambers of the battery. In the present embodiment of this invention each line 44 extends from the oven doorways, at a level accessible to an operator on the coke guide machine 37, downwardly alongside of the adjacent buckstay 29 to the level of the transverse beams 20, and thence across the battery underneath the oven mat 18, through the accessible basement passageways 19, to the pusher side of the battery, thence upwardly to beneath the pusher side bench 31 and outwardly to a position accessible from the pusher

machine. At the latter region actuating means 45 are provided, operable when pneumatic pressure is imposed in the individual lines 44, to actuate operating means 46 for a limit switch comprising means in the form of an actuating blade 74 for closing an interruption 48 in the form of spaced apart contacts in the electrical circuit 49 for the motor 36 for driving the pusher ram. This switch blade 74 closes the interruption 48 of the circuit 49 to permit the operator to drive the ram inwardly into the oven chambers when the pneumatic pressure is imposed on the actuating means 45 in the respective pipe lines 44 and is normally urged to move to open position, which it does when the fluid pressure is off in the lines, and when the operating means 46, for the limit switch on pusher machine 25 is disconnected from the fluid pressure lines.

These lines 44 are all individually controlled 20 from the coke guide machine by its operator by the co-action of means accessible only from the coke guide machine with only one of the lines at a time, for causing fluid pressure (pneumatic) in the line to operate the actuating means 45 25 on the pusher side to actuate the operating means 46 for the limit switch, to close the interruption 48 in the electrical circuit 49 for the motor 36 to advance the pusher ram 35 when the operator of the pusher machine operates the controller for 30 that purpose. Converse operation by the coke guide machine operator causes a drop in the pneumatic pressure in the line, and the switch for the pusher ram motor circuit opens, immediately preventing further advance movement, 35 accidentally or otherwise, by the operator of the pusher machine.

In the present embodiment of the invention, the pneumatic pressure is supplied individually to the individual fluid pressure lines as follows:

40 On the coke guide machine 37 is mounted an electric motor 50 operable at will by the operator and connecting by speed reducer 51 with an air compressor 52 having compression cylinders 53. The air under pressure is stored in receiver 54, 45 from which the air is fed through line 55 having pressure reducing valves 56 and a flexible metal hose 57 attached at the end of the line 55 on the coke guide machine. At its other end the flexible metal hose is provided with a coupling element 58 adapted to be quickly attached to and detached from a companion coupling element 59, one on each of the lines 44 and at a level accessible to the coke guide machine operator as the machine 37 is moved along the side of the battery 55 on the bench.

The lines have downward extensions 60 below where they pass across under the oven battery, which extensions are provided with removable caps 61, for drainage of said lines with mechanical operation. The lines 44 on the coke side are bent out near the beams 21 in order to pass around the flanges of the buckstays and over the beams 21 to avoid penetrating the beams for passage of said pipes.

65 In the embodiment of the invention, as shown on the drawing, when the operator of the coke guide machine 37 is about to prepare an oven 11 for discharge of coke, he advances his machine 37 alongside the same until the door extractor 70 machine 41 is in front of the door 23 then he operates its motors to remove the door 23, whereupon he then operates the motor to move the whole coke guide machine 37 so as to position the door 23 out of the way of the door frame of the oven and position the coke guide 42 in front of

the open doorway, and then the rack and pinion is operated to press the coke guide 42 in place against the battery face or door-jamb. It is then that he attaches the flexible hose 57 to the connection 59 on the line 44 for that oven, whereupon air under pressure flows from the receiver 54 through the lines 55 and 44 to the actuating means 45 for actuating the limit switch having blade 74 for the pusher ram 35. Due to the construction of the particular coke guide machine 37 shown on the drawing, this necessitates, for convenience of operation by the operator, the connection of the flexible hose 57 with the fluid pressure line 44 two ovens away from the oven actually being operated. As will be seen from Fig. 2, as a result, each fluid pressure line 44 is, as a consequence, individualized to that oven that is two ovens to one side thereof, towards the bottom as viewed in Fig. 2. On the pusher side 14 this necessitates, in the present embodiment of the invention, upper branch lines 62, to accommodate both the alternative manual operation, hereinafter described and the convenience of access to the same by the pusher machine operator of the mechanism.

In the improved control apparatus above described, there is as a result improved safety of operation. However, there is still left chance for error in operation rendering futile the precautions taken, notwithstanding they are all fully utilized.

The propelling of the coke guide and pusher machines may still take place accidentally or intentionally along the battery to an extent to cause the coke guide car to interfere with the pushing of the coke as a cake out of the oven, during pushing, thus jamming up the coke cake in the oven chamber under compression of the ram; and the pusher machine may still be moved causing the ram to gouge the oven heating walls, while the system is interlocked. In addition the pusher machine is a large and cumbersome machine and the exigencies of operation from the same by an operator from his control cabin is such as to make highly desirable the provision of some means for automatically interconnecting the limit switch for the pusher ram circuit with the proper fluid pressure line when actuated or energized by the coke guide machine operator.

To this end the present invention provides improvements in the automaticity of operation in both respects as well as a very highly needed alternative manual operation available with the same mechanism for use in energizing.

Referring to Figs. 1 and 3, there is provided means automatically operated by the movement of the coke guide operator in causing the pneumatic pressure in a line 44 to actuate the operating means 45 for the limit switch for the pusher ram, for preventing the movement of the coke guide machine alongside the battery during the time the pusher ram may be advancing under the power of its electrical circuit for that purpose. Said means is automatically operated to permit the coke guide machine to be moved along the battery by the movement of the coke guide operator in causing the pneumatic pressure to release the said actuating mechanism to interrupt the electrical circuit for advancing the pusher-ram 35.

Advantageously, as shown, this automatic means comprises the novel employment of a simple mechanism of the type of the conventional telephone receiver hook 63. As shown, there is provided a switch stand 64 provided with a limit

switch comprising an interruption 65 in the electrical circuit of a motor (not shown) for propelling the coke guide machine along the battery. Pivotally mounted on the stand, the hook is adapted to receive the flexible hose 57 when detached from the lines 44. Movable with the hook 63 is a contact element adapted, when the hook is depressed on receiving the flexible hose, to close the interruption 65 in the electrical circuit for propelling the coke guide machine. The hook is normally urged to move the contact element out of electrical contact with the interruption 65 for the circuit, to open the same, which it does when the hose is removed from the hook by the coke guide operator in attaching it to the respective lines 44.

Referring to Figs. 1 and 2, there is shown like means, automatically operable when the pusher ram electrical circuit, for advancing the pusher ram, is actuated by the interlocking mechanism, for preventing movement of the pusher machine alongside the battery under the action of the electrical motor (not shown) for propelling the pusher machine. As shown, this comprises switch stand 66, receiver hook 67 pivotally mounted thereon, an interruption 68 in the electrical circuit for the motor for propelling the pusher machine. The hook 67 is adapted to receive a flexible metal hose 69 and to be depressed when so doing, at which time a contact element is thereby operated to close the interruption in the electrical circuit. The hook is normally urged to move upwardly, which it does when the hose is removed from the receiver, upon which movement, the contact element for the interruption is moved to open the interruption in the electrical circuit that is used to supply current for propelling the pusher machine along the battery, thus preventing such movement of the machine automatically. This hose is as shown, manually operated, at the will of the operator of the pusher machine 25 at a level readily accessible to him from his operating platform or cabin.

Referring to Figs. 1, 1a, and 2, there is shown the novel means of invention for automatically effecting the interlocking of the electrical circuit for advancing the pusher ram, individually with the individual fluid pressure lines. Advantageously, this takes a form which employs in a novel manner simply the movement of the pusher machine into its pushing position designated by the pushing schedule, for pushing the designated coke ovens, to effect the interlock.

In carrying out the pushing schedule, the operator starts at one end of the battery and moves the machine successively therealong, pushing the ovens seriatim as designated on the schedule, then for the next pushing run the machine is returned to the initial starting point and the next set of pushing operations begins. In moving from oven to oven of the designated ovens in the series to be pushed, the machine is moved quite rapidly, as much as 400 feet per minute.

For effecting the interlock, a bracket 70 is provided on the front of the pusher machine 25 that is next adjacent the pusher alleyway and bench. This bracket 70 supports the interruption 48 in the electrical circuit 49 leading to the motor 36 for propelling the gear that drives the rack secured by the pusher ram 35. This interruption contains two contact points. Two leads 72 connect with the motor 36 and both connect with a single one of the two contact points. The purpose of this is to enable the pusher ram operator to operate the circuit to retract the ram

at will, such circuit not being influenced in any manner by the interlocking mechanism. For advancing the ram however, connection must be made between the two contact points to connect the third lead 13 to the motor 36 with one of the other two leads 72 to complete the circuit for advancing the pusher ram into the ovens. It is this circuit that is the subject of the interlock and under the control of the coke guide machine operator.

For effecting the interlock the switch blade 74 is provided to move into and out of contact with the above mentioned two contact points. As shown in full lines in Fig. 1a, the switch is open, its closed position being indicated in dotted lines.

For actuating the switch a depending lever 75 rides between the prongs of a fork having rollers as shown, for ease of actuation of the switch blade 74 to its open and closed positions.

The lever 75 is carried by a rod 76 reciprocable in a bearing 77. Spring 78 normally urges the rod and lever, and the arcuate sliding-contact rail 46 hereinafter described, toward the series of individual actuating means 45 for the arcuate sliding-contact rail, which normal position is the open position for the limit switch.

Each of the fluid pressure lines 44 terminates in one of such actuating means 45. It comprises a fluid pressure cylinder having a piston therein, to which is secured an actuating rod extending through one end of the cylinder and terminating in a rounded knob (or roller) for free sliding contact with the arcuate sliding-contact rail 46, for the actuating of the latter to operate its limit switch (74, 48).

Within the cylinder 45 the rod is encircled by a spring normally urging the knob or roller out of the path of the sliding-contact rail 46. When the coke guide operator operates the individual fluid pressure lines to cause fluid pressure to act in their cylinders 45, the piston and rod are actuated to move the knobs or rollers into engagement with the sliding contact rail 46, when it is in position in the path of the cylinders for the individual ovens.

The sliding-contact rail advantageously diverges from its high point 79 at which the actual reversal of the limit switch takes place, this diverging being outwardly gradually away from the cylinders 46, in the direction of movement of the pusher machine, in carrying out the pushing schedule and this for a distance of at least three ovens and their intermediate heating walls.

This has been found to be an unexpected important feature in practical operation, since it will be found that with a shorter sliding contact rail, and the rough handling of the machines that obtains, and the rate at which it is moved along the battery, from an oven just pushed to the next one to be pushed, that the actuating rods may bend or break, and leaks spring in the air cylinders rendering the interlocking system inoperative.

For adjusting the degree of movement of the sliding-contact rail for actuating the switch, an interchangeable fitting 80 is interposed between the same and the rod 76.

The sliding-contact rail 46 also extends, and diverges outwardly, in the opposite direction from the high point to accommodate backing up, upon over-running of an energized air cylinder by the pusher machine. The rail is also mounted for movement on rollers 81 and is keyed to brackets 82 by means of pin and slot connections 83.

Referring to Figs. 1 and 2, provision is made for optional manual operation of the electrical circuit interlock for the pusher ram, in event this is necessary due to some unforeseen difficulty in operation of the automatic mechanism therefor.

As will be seen from Fig. 1, the fluid pressure lines 44 for automatic operation lead from beneath the pusher bench to a level of just above the wheels of the pusher machine. In each line 10 a valve 84 is provided, to be opened for automatic operation and to be closed for manual operation. From above the valve 84, the branches 62 of the individual fluid pressure lines 44 lead upwardly above the pusher bench to a level that is accessible to the operators from an operating platform. These branch lines terminate in a depressible self-sealing valve of the type used on pneumatic tires. On a bracket 85 on the pusher machine, an air pressure cylinder 86 is provided 15 having like the cylinders 45, a similar piston and piston rod extending through one end of the cylinder and terminating in contact points. The piston is normally urged to retract the piston by a spring. The short flexible metal hose 69 is connected with this cylinder and is provided at 20 its other end with a coupling for connection with the valved end of branch lines 62, which latter also have a valve 88 for closing the branches 62 when not in manual operation. A separate 25 switch 89 is provided in the motor circuit for the pusher ram which is a duplicate of that for the automatic interlocking. This separate switch is cut into the circuit so as to by-pass, as shown, the automatically operated switch when manual 30 operation becomes necessary for advancing the pusher ram.

The means for supply of air under compression to the lines 44 may be provided, without departing from the spirit and scope of the present invention, in various other manners. For instance 40 the motor, air receiver, and feed lines, as shown for the supply of compressed air from the coke guide machine, may instead be installed on the pusher machine, means being provided at the coke side for closing that end of the lines 44, such as, for instance, a valve accessible for operation from the coke guide machine and adapted to close the end of the respective lines, and to be opened, as to the atmosphere to bleed the respective lines. Further, the means for supplying the compressed air may comprise connection of the lines 44 with the decarbonizing air main conventionally employed in coke oven batteries for supplying decarbonizing air to the rich gas fuel 45 feed channels that feed the combustion flues, said decarbonizing air being fed to said channels while they are idle to gas flow, to burn off deposited carbon in said channels, their ports and orifices; or a separate main and air compressor 50 may be employed but disposed in the oven battery basement, or alongside the battery, for feeding air under pressure to the lines 44.

An electric indicator light or lights may be provided to indicate whether the individual actuating means 45 of the lines 44 are individually 55 in position or not to actuate the operating means for the switch to advance the pusher ram into an oven chamber.

Instead of coupling the compressor to the oven 60 pipe line 44 by means of a flexible hose, the end position of the upwardly extending part of the pipe line may be arranged horizontally in a buckstay or in a special mounting carried by the masonry or other part of the oven structure and 65 surrounded by a suitable flat or other valve seat-

11

providing member against which may seat a resilient and/or resiliently carried self-sealing cup or nozzle carried by one of the tubes mounted on the pusher machine and connected pneumatically to the said compressor and so arranged that it can be advanced towards the battery and moved away from the battery as desired. Thus when it is desired to couple the compressor to the pipe line extending below an oven, the said self-sealing cup is advanced towards the battery and engaged with the seat around the adjacent end of the said pipe line. The advancement of the self-sealing cup towards the said seat may be effected automatically by a portion of the pusher machine or the coke guide machine movable to or from the battery or it may be effected manually. The self-sealing cup may be on the said tube and the seat for the cup on the end of the pipe line instead of the reverse arrangement above described.

Any other suitable automatic or manual means for coupling the oven pipe line with the compressor may be employed instead of those mentioned by way of example above.

On the coke guide machine may be mounted a pipe which may be referred to as a "dead end pipe," adapted to be connected by a short length of flexible metal hose with the coke side end of the oven pipe 44 extending below the oven for which the coke guide machine is aligned at any particular time. However, instead of using a quickly detachable and attachable hose of this type for connecting the coke guide machine pipe to the oven pipe line, a manually operable or automatically operated resiliently mounted self-sealing coupling member of the kind described above (with reference to the pusher side of the machine) or any other suitable form of coupling, may be employed.

The said pipe lines 44 may be furnished on the coke guide machine with a quick release means as a valve, whereby the pipe may be sealed so as to prevent the escape therefrom of pressure fluid supplied to the pipe from the oven pipe line and whereby the pressure in the latter may be released when desired.

If, for one reason or another, it is desired to stop the forward stroke of the ram the workman at the coke side of the battery can do this by opening the quick release valve. If desired, an electric indicator light may be adapted to light in the pusher machine when the said release valve is opened. The release valve is also adapted to be used to open the interlocking system to the atmosphere at the completion of the "pushing" operation so that the hoses of the system may be disconnected from the oven pipe with safety.

In another arrangement, the coupling may comprise a resilient or like self-sealing cup or similar device such as a tube arranged upon the coke guide machine horizontally and at right angles to the longitudinal side of the coke oven battery. The tube is slidably carried in a suitable guide bracket upon the coke guide machine and is fixed to another bracket on the coke guide machine movable in the direction of the axis of the said tube and with respect to the guide bracket slidably carrying the tube. The bracket with which the tube is rigidly associated may be fixed to the coke guide which is movable to and from the battery in order to engage it in the door frame or to disengage it from the latter.

The battery end of the said tube is provided with a metal cup containing a resilient, e. g.

soft rubber, cup washer or equivalent member supported on the inside by a further metal cup, the said resilient washer projecting beyond the battery edge of the metal cup within which it is contained so that its free edge may seat resiliently upon the portion of the buckstay or other flat seat surrounding the end of the oven pipe line to which the said tube is to be coupled.

Normally, the said cup washer will be clear of the battery side but when the coke guide machine has been aligned with an oven of the battery and the coke guide moved up into contact with the oven, the resilient cup washer will automatically be coupled to the end of the pipe line of the corresponding oven. A strong spring may be provided on the tube and arranged so that it will assist in the withdrawal of the cup washer from the battery when the coke guide is withdrawn from the oven, and the said tube may be capable of resilient axial movement independently of the coke guide so as to allow for any inequalities in the condition of the various buckstays or other parts of the battery with which the cup washer has to engage.

The end of the said tube remote from the cup-washer and thereof, is coupled by a flexible or other suitable conduit to the compressor and a 3-way control valve may be furnished whereby this connection may be interrupted and the compressor opened to exhaust or to other apparatus on the coke guide as desired.

The invention as herein above set forth is embodied in particular form and manner but may be variously embodied within the scope of the claims hereinafter made.

I claim:

1. The combination with: a pusher machine for a horizontal coke oven battery; a ram mounted on said machine; and a control means on said pusher machine comprising an electrical circuit control switch normally rendering said pusher ram inoperative in the forward direction; and pneumatic fluid pressure operated means individualized to the respective ovens of said battery and adapted to operate said switch to enable the pusher ram to make its forward stroke only when its pusher machine and a coke guide machine are aligned at opposite sides of a said battery with one and the same oven; and means on a said coke guide machine to prevent operation of a motor for driving said coke guide machine, said means being automatically operable by the movement of an operator of the coke guide machine in individually-controlling the flow of pneumatic pressure in a line individual to an oven when aligned with the coke guide; of an arcuate sliding contact rail on the pusher machine, said rail being normally urged towards said pneumatically operable actuating means for the fluid pressure lines and operable by individual sliding engagement with said pneumatically operable actuating means of the individual fluid pressure lines, when the latter are energized, to operate the switch for advancing the pusher ram; said contact rail diverging gradually away from the said actuating means in the direction of movement of the pusher machine for pushing, for a distance of at least three oven chambers and their intermediate heating walls; manually operable means for optional manual interconnection of the pusher ram advancing circuit individually with the individual fluid pressure lines, said means comprising a switch for cutting into the pusher ram advancing circuit so as to by-pass 60

75 aforesaid automatically operated switch therefor;

and manual connection means accessible to the operator's station on the pusher machine for manual connection with the individual fluid pressure lines, for the optional operation of the manually operable means; and means on the pusher machine, operable by the operator, for automatically preventing operation of a motor for propelling the pusher machine alongside the battery while the pusher ram circuit is completed by the aforesaid fluid pressure line interlock, and for automatically permitting such propelling movement while the pusher ram circuit is broken by the aforesaid fluid pressure line interlock.

2. The combination with: control means on a pusher machine for a horizontal coke oven battery, comprising an electrical circuit control switch normally rendering a pusher ram on said pusher machine inoperative in the forward direction; and pneumatic fluid pressure operated means individualized to the respective ovens of said battery and adapted to operate said control switch to enable the pusher ram to make its forward stroke only when its pusher machine and a coke guide machine are aligned at opposite sides of a said battery with one and the same oven; and means operable by the movement of an operator on the coke guide machine for automatically individually controlling the flow of pneumatic pressure in a line individual to an oven only when it is in alignment with the coke guide; of operating means movable from oven to oven with the pusher machine for automatically operating the switch for the pusher ram circuit, said operating means being operable by the actuating means of individual lines when energized to operate the switch for advancing the pusher ram, manually operable means for optional manual inter-connection of the pusher ram advancing circuit individually with the individual fluid pressure lines, said means comprising a switch for cutting into the pusher advancing circuit so as to by-pass the said automatically operated switch, and means accessible to the pusher machine operator's station for manual connection with the individual fluid pressure lines for optional operation of the manually connected switch.

3. The combination with: control means on a pusher machine for a horizontal coke oven battery, comprising an electrical circuit control switch normally rendering a pusher ram on said pusher machine inoperative in the forward direction; and pneumatic fluid pressure operated means individualized to the respective ovens of said battery and adapted to operate said control switch to enable the pusher ram to make its forward stroke only when its pusher machine and a coke guide machine are aligned at opposite sides of a said battery with one and the same oven; and means operable by the movement of an operator on the coke guide machine for automatically individually controlling the flow of pneumatic pressure in a line individual to an oven only when it is in alignment with the coke guide; of operating means movable from oven to oven with the pusher machine for automatically operating the switch for the pusher ram circuit, said operating means comprising an arcuate sliding-contact rail normally urged towards the actuating means for the fluid pressure lines and operable by sliding individual engagement with the actuating means of individual lines when energized to operate the switch for advancing the pusher ram, said rail diverging gradually away from the said actuating means in the direction of movement for pushing for a distance of at

least three oven chambers and their intermediate heating walls.

4. The combination with: control means on a pusher machine for a horizontal coke oven battery, comprising an electrical circuit control switch normally rendering a pusher ram on said pusher machine inoperative in the forward direction; and pneumatic fluid pressure operated means individualized to the respective ovens of said battery and adapted to operate said control switch to enable the pusher ram to make its forward stroke only when its pusher machine and a coke guide machine are aligned at opposite sides of a said battery with one and the same oven; and means operable by the movement of an operator on the coke guide machine for automatically individually controlling the flow of pneumatic pressure in a line individual to an oven only when it is in alignment with the coke guide; of operating means movable from oven to oven with the pusher machine for automatically operating the switch for the pusher ram circuit, said operating means being operable by the actuating means for individual lines when energized to operate the switch for advancing the pusher ram, and means on the coke guide machine automatically operable by the movement of its operator in individually controlling the flow of pneumatic pressure to, and release of it from, the individual fluid pressure lines, for preventing the operation of a motor and for permitting the operation of the motor, respectively, in driving the coke guide car along the coke side of the battery.

5. The combination with: control means on a pusher machine for a horizontal coke oven battery, comprising an electrical circuit control switch normally rendering a pusher ram on said pusher machine inoperative in the forward direction; and pneumatic fluid pressure operated means individualized to the respective ovens of said battery and adapted to operate said control switch to enable the pusher ram to make its forward stroke only when its pusher machine and a coke guide machine are aligned at opposite sides of a said battery with one and the same oven; and means operable by the movement of an operator on the coke guide machine for automatically individually controlling the flow of pneumatic pressure in a line individual to an oven only when it is in alignment with the coke guide; of operating means movable from oven to oven with the pusher machine for automatically operating the switch for the pusher ram circuit, said operating means being operable by the actuating means of individual lines when energized to operate the switch for advancing the pusher ram, and traversal-lock means on at least one of the two, coke guide and pusher machines operable by its operator for automatically preventing operation of a motor for propelling the machine alongside the battery while the pusher ram circuit is completed through the aforesaid fluid pressure line interlock, and for automatically permitting such propelling movement when the pusher ram circuit is broken by release of fluid pressure in the fluid pressure line interlock.

6. Apparatus as claimed in claim 5 and in which the traversal-lock means comprises a flexible metal hose for detachable connection with each of the individual fluid pressure lines, an interruption in an electrical circuit for the motor for propelling the machine alongside the battery, a telephone receiver hook having means

for closing the interruption and normally urged to open position, said hook being disposed in position to support said hose when detached from the individual fluid pressure lines and to be moved thereby, thus placing the means for closing the interruption in its closing position.

7. Apparatus as claimed in claim 5 and in which the traversal-lock means comprises a flexible metal hose for detachable connection with each of the individual fluid pressure lines, an interruption in an electrical circuit for the motor for propelling the machine alongside the battery, a receiver having means for closing the interruption and normally urged to open position, said receiver being disposed in position to sup-
